ENGINE STARTER

John W. Fitzgerald, Milwaukee, Wis., assignor
to Briggs & Stratton Corporation, Milwaukee,
Wis., a corporation of Delaware

Application February 20, 1939, Serial No. 257,437

3 Claims. (Cl. 74—9)

This invention relates to engine starters, and refers particularly to starters of the "Bendix" type.

One of the objects of the present invention is to provide a starter of unitary construction, and one which does not require a separate pinion stop to be secured to the motor shaft.

Another object of this invention is to provide a starter which employs a rubber cushioning collar to transmit the torque from the motor shaft to the pinion, and also absorbs the shock incidental to improper meshing of the gears.

Another object of this invention is to provide an engine starter of the character described wherein the translation of the pinion to and from its operative position is effected through a cam connection as distinguished from the more conventional use of screw threads.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a side view of an engine starter constructed in accordance with this invention, parts thereof being broken away and in section;

Figure 2 is a view similar to Figure 1, showing the position of the parts during improper meshing of the gears;

Figure 3 is a view similar to Figure 1, showing the parts in the positions they assume during the actual transmission of the driving force to the engine ring gear;

Figure 4 is substantially a longitudinal sectional view taken through Figure 1 on the plane of the line 4—4; and

Figure 5 is a perspective view of the pinion actuator and the rubber driving element shown separated from the rest of the structure and from each other.

Referring now particularly to the accompanying drawings in which like numerals indicate like parts, the numeral 5 designates the motor shaft of the starter, which, as is customary, extends past the ring gear 6 of the engine. The

starter mechanism, indicated generally by the numeral 7, is applied to the shaft as a unit and comprises a pinion 8 slidably mounted on the shaft for longitudinal movement into and out of mesh with the engine ring gear.

Extending outwardly from the pinion is a sleeve 9, which, in the inoperative position of the pinion, has its outer end adjacent to a fixed abutment in the form of a collar 10 which is secured on the shaft. The pinion sleeve 9 mounts two spiral cams 11 and 12 between which a correspondingly cam-shaped pinion actuator 13 is interposed. To enable assembly, the outer spiral cam 12 is brazed or otherwise secured to the sleeve 9 after the pinion actuator has been applied.

The actuator 13 is tubular and is freely rotatable and slideable on the sleeve 9 but has no endwise motion with relation to the spiral cams 11 and 12. It is only through relative rotation between the actuator and the sleeve that longitudinal motion is permitted the actuator.

Rotation is imparted from the shaft to the pinion actuator to effect translation of the pinion into mesh with the ring gear through a torsionally and endwise resilient driving connection, indicated generally by the numeral 14.

This driving connection comprises a rubber collar 15 interposed between a flange 16 on the collar 10 and a flange 17 on the pinion actuator. A cylindrical shell 18 having its edges turned over the flanges holds the same against spreading beyond a predetermined distance to maintain the rubber collar under a degree of compression.

Vulcanized to the opposite faces or ends of the rubber collar are metal washers 19, the outer faces of which have driving lugs 20 projecting therefrom to engage in recesses or holes 21 in the adjacent flanges. Hence, each flange is positively connected with the adjacent face of the rubber collar which is important in this construction inasmuch as the driving torque is transmitted without increasing the compression of the rubber collar.

In operation, the initial rotation of the actuator 13 by virtue of its resilient driving connection with the shaft propels the pinion forwardly into mesh with the ring gear. The forward propulsion of the pinion is limited by the cam connection between the pinion sleeve and the pinion actuator, as illustrated in Figure 3, this being brought about by the fact that the spiral cams terminate in abutments which engage each other, as at 22 in Figure 3.

When the engine begins to operate under its

own power, the overrunning action of the pinion through the cam connection retracts the pinion in the customary manner.

It is to be observed that when the load of the engine is taken up, there is a positive driving connection from the pinion actuator to the pinion through the abutting ends 22 of the cams, as shown in Figure 3, but the actual picking up of the load is cushioned through the torsional resiliency of the rubber collar.

The endwise resiliency of the collar absorbs shock incidental to improper meshing of the gears, as shown in Figure 2. In this instance, the obstruction of forward propulsion of the pinion, through the action of the cam connection between the pinion sleeve and the actuator, causes the flanges 16 and 17 to move toward each other to compress the rubber collar. This action continues until the friction between the inclined faces of the complementary cams overcomes the friction at the abutting teeth, whereupon the pinion is turned sufficiently to effect proper meshing.

From the foregoing description taken in connection with the accompanying drawings, it will be readily apparent that this invention provides an engine starter which is capable of being mounted in the motor shaft as a complete unit, and that no separate stop is required to limit the motion of the pinion toward the ring gear.

What I claim as my invention is:

1. In an engine starter: a power shaft; a pinion movable along the shaft to and from an operative position in which it meshes with the ring gear of an engine; a sleeve extending from said pinion; an actuator for the pinion freely encircling a medial portion of the sleeve; a flanged abutment secured to the shaft adjacent to the end of the sleeve; an annular flange on the actuator medially of its ends; a resilient driving connection between the shaft and the pinion actuator including a rubber collar confined between said flanges and providing the sole driving connection between the shaft and the actuator; and a separate cam connection between the actuator and the pinion sleeve at each side of the actuator flange operable sequentially to move the pinion along the shaft to and from its operative position upon relative rotation between the pinion and its actuator, one of said

cam connections including means for arresting movement of the pinion toward its operative position and for drivingly connecting the pinion with the actuator for rotation therewith.

2. In an engine starter: a power shaft; a pinion movable along the shaft to and from an operative position in which it meshes with the ring gear of an engine; a sleeve extending from one end of said pinion; separate spaced apart cam surfaces on said sleeve; a substantially tubular pinion actuator encircling the sleeve and confined between the cam surfaces thereof; a cam connection between each end of the actuator and the adjacent cam surface of the sleeve preventing axial movement of the pinion with respect to the actuator except upon relative rotation between said parts, one of said cam connections being operable to propel the pinion to its operative position in which it meshes with the ring gear, and the other cam connection being operable to retract the pinion upon starting of the engine; co-operating means included in said other cam connection for limiting relative rotation between the actuator and the pinion and for drivingly connecting the pinion with the actuator for rotation therewith; and a torsionally and endwise resilient driving connection between the shaft and the actuator.

3. In an engine starter: a power shaft; a pinion movable along the shaft to and from an operative position in which it meshes with the ring gear of an engine; a sleeve on the pinion; separate endwise spaced apart cam surfaces on said sleeve; a substantially tubular pinion actuator encircling the sleeve and confined between the cam surfaces thereof; a cam connection between each end of the actuator and the adjacent cam surface of the sleeve, said cam surfaces being engaged at all times so that no lost motion exists between the pinion and the actuator whereby axial movement of the pinion with respect to the actuator is possible only upon relative rotation between said parts, said cam connections being sequentially operable to propel the pinion to its operative position in which it meshes with the ring gear and to retract the pinion upon starting of the engine; and a torsionally and endwise resilient driving connection between the shaft and the actuator.

JOHN W. FITZ GERALD. 50
